Des. 1553

Clemir J. Ney. of Lowell, Mass.
Assignor to
The Lowell Manufacturing Co. of same place.
Letters Patent No. 1553, dated March 18, 1862.

The schedule referred to in this Letter Patent and making part of the same.

Wall upon which it may be used;

Know, that S. Clemir J. Ney, of Lowell in the
County of Middlesex and State of Massachusetts, have originated and
designed a new Pattern for Carpets or other fabrics, of which the following
is a full, clear and exact description, reference being had to the accompanying
spanshing drawings, making part of this Specification.

This Specification refers to that part of the drawings
lying on the left of the blue line.

Fig. A and B, when matched from an eight point-
ed block surrounded by a frame of sprigs.

Fig. 1 and 2, when matched from a block similar
to that formed by figs. A. and B.

C, in the centre is an outline figure, or double frame,
having small blocks attached to its corners.

In corners 3. 4. 5. 6. are fourths of figures similar to C.
Lying between figs. A. and 2. B and 1. respectively, are solid blocks having
arms extending towards the centre and corners.

The remaining portions of the design are repetitions
of the before mentioned figures.

The colors employed for the different portions of
the design may be varied, to suit the taste and wish of the manufacturer.

Claim. What I claim as my invention and desire to secure
by Letters Patent, is the design or pattern, for carpets or other fabrics, herein
set forth. *Witnesses.*
